ABSTRACT OF THE DISCLOSURE

A stylishly unique neckpiece for occasional wear by both men and women expressly designed for use when attired for formal, semiformal, sportswear and such occasions as call for a fashionably attired appearance. It comprises a fabric-covered bendably pliant form which spans the gap between the shirt collar ends and conceals the buttoned ends of the neckband and, being ready-made, is attached by a hook-equipped clip. Broadly, the form is covered by decorative ribbons oriented with a depending ornate puff.

This invention relates to neckwear which is unlike conventional four-in-hand and bow ties and which, generally stated, falls in the field of loose-fitting ascot ties, neckerchiefs and the like and has to do, more particularly, with a ready-made fashionable neckpiece which can be clipped in place to occupy a position concealing the buttoned neckband-ends and bridging the usual gap between the spaced downturned ends of the shirt collar.

Persons conversant with the field of invention under advisement are aware that many patents covering ready-made and fashionably attractive collar-supported neckpieces have been granted. It is also common practice to provide prefabricated neckties with various types of attaching clips. It is an object of the present invention to improve upon ready-made neckpieces by providing an adaptation which lends itself to acceptable use by either men or women. The adaptation herein disclosed is an innovation which is styled to orient itself with the wearer's shirt collar.

Briefly the neckpiece herein comprehended is of a composite type which is characterized by a form which is substantially crescent-shaped in front elevation and has divergent upturned end wings which can be manually tucked between the usual downturned collar-ends and associated portions of the neckband of the wearer's shirt. This form preferably comprises a suitable ply of bendable plastic material which is encased in a jacket made of silk or other necktie material. In addition to an attaching clip and attractive jacketing means the front face of the covered form is provided with longitudinally positioned first and second colorful ribbons also made of necktie material. These ribbons extend lengthwise of the fabric-jacketed-form and are attached to the jacketing material, the adjacent longitudinal edges of the ribbons being overlapped and presenting a cummerbund-like appearance. In addition, the central bottom portion of the thus decorated form is provided with a suitably pleated or gathered silk or equivalent ornament which provides a depending puff. Then too and if desired, a plurality of individual selectively usable relatively small pennant-like pendants are provided and have lower ends dangling below the bottom margin of the puff.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIG. 1 is a front elevation showing a fragmentary portion of a collar-attached shirt and showing, what is

2

more significant, the neckpiece cooperable with the collar-ends and constructed in accordance with the present invention.

FIG. 2 is an enlarged fragmentary view taken approximately on the plane of the vertical central section line 2—2 of FIG. 1.

FIG. 3 is a rear elevation showing the plastic or equivalent form with the attaching clip mounted centrally thereon and with the turned serrated or scalloped edges of the jacket stitched in place.

FIG. 4 is a front elevation of the jacketed or encased form showing the pouch-like puff and how it is gathered, shaped and stitched in place on the fabric jacket of the form.

FIG. 5 is a front elevation similar to FIG. 4 and showing one of the longitudinal decorating ribbons applied.

FIG. 6 is a view also in front elevation and similar to FIG. 5 and showing the second or upper ribbon applied with both ribbons overlapped to resemble a miniaturized cummerbund.

FIG. 7 is a rear elevation similar to FIG. 3 but showing the finishing ply of the aforementioned jacket stitched in place and showing several optionally usable pendants and how they are used to contribute to the over-all ornate appearance of the neckpiece.

And FIG. 8 is a view in perspective showing a fragmentary portion of the rear side of the neckpiece and illustrating several male snap fasteners and a single pendant with its attaching snap fastener at the upper end thereof, the pendant being detached.

With reference now to the views of the drawings and with respect to FIGS. 2 and 3, it will be seen that the aforementioned form is denoted by the numeral 10 and when viewed from either the forward or rearward side it is substantially crescent-shaped in general appearance. Specifically it comprises a crescent-shaped ply of appropriate bendably conformable sheet plastic material as at 12 (FIG. 2). The wing portions 14 (FIG. 3) are upturned and diverge slightly and have a spread which permits the form to be tucked into place, that is, between the downturned end portions 16 of the collar 18 carried by the shirt 20. As usual the collar embodies a neckband 22 having overlapping free end portions 24 connected by a suitable button 26 in the manner illustrated in FIG. 2. This form is encased or enclosed in a snug-fitting silk or equivalent jacket denoted generally by the numeral 28 and having marginal edge portions 30 turned over the form and having serrated or scalloped edges 32 stitched or otherwise connected in place as at 34. The left and right end portions (FIG. 3) are also turned-in as at 36 and likewise stitched at 38. This jacket also includes a suitably shaped ply 40 as shown in FIG. 7 and whose edges overlap the turned-in portions 30 and are scalloped and stitched in place as at 42. This cover 40 is a part of the jacket and conceals or encloses the wing-shaped clip 44 (FIG. 3), the clip being suitably secured and having an upstanding hook 46 to engage over the buttoned neckband ends as shown in FIG. 2.

It will be evident from the detailed description thus far given that the plastic or equivalent sheet-type form 10 is adequately enclosed in a cloth or equivalent jacket and embodies as a component part the hook-equipped attaching clip.

With reference now to FIG. 4 and looking at the front of the covered form, it will be seen that it is centrally provided with an ornate depending component which is here shown as pouchlike in form and is made of appropriate necktie material and is gathered as at 48 to provide a segmental depending puff 50. This puff has its pinked or scalloped end portions 52 superimposed

upon and stapled as at 54 to the front of the form jacket.

Referring now in sequential order to FIG. 5, it will be seen that a first elongated silk or equivalent band or ribbon is denoted at 56 and it is extended across the front or forward side of the structure shown in FIG. 4 with the end portions 58 provided with return bends and stitched in place. A lower edge portion 60 overlaps and conceals the gathers 48 and end portions 52 of the puff 50. A second and complementary elongated ornamental ribbon is provided as at 62 and this is similar to the ribbon 56 and has its ends turned toward the rear as at 64 and stitched in place as shown in FIG. 7. The lower lengthwise edge portion 66 of the second ribbon overlies or overlaps the ribbon 56. These two ribbons, considered in conjunction with the depending puff 50, provides what is herein described as a miniaturized cummerbund effect.

With reference now to FIGS. 7 and 8 and particularly with reference to FIG. 8, it will be seen that the rearward side of the structure is provided with spaced individually usable male snap fasteners 68 which serve to accommodate female snap fasteners 70 on upper end portions 72 of the ornamental pendants 74. When the several pendants are attached as shown in FIG. 7 the lower ends dangle below the curvate lower edge of the puff to provide the dignified appearance suggested in FIG. 7, that is, when viewed from the front.

This neckpiece when constructed and worn as illustrated in FIG. 1 provides the desired full-dressed look suitable for well-groomed and distinctively attired occasions.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention.

What is claimed as new is as follows :

1. For quick-attachable use on the button-connected-ends of the neckband of a collar attached shirt, a ready-made composite neckpiece comprising, in combination, a form said form being crescent-shaped in elevation and designed and conformably adapted to span and conceal said end-wings which can be manually tucked between the usual downturned collar-ends and coacting portions of said neckband, said form comprising a ply of requisite bendably pliant plastic material and having forward and rearward faces, said rearward face being provided with an attached form positioning clip, said clip having a supporting and retaining hook capable of being detachably hung over the button-connected-ends of said neckband, and a snug-fitting fabric jacket means attached to and completely encasing said form.

2. The neckpiece defined in and according to claim 1, and wherein said hook is integral with a median upper marginal edge of the body portion of said clip and pro-

jects upwardly to a readily attachable position above the plane of said upper marginal edge.

3. The neckpiece defined in and according to claim 1, and ornate means supplemental to, attached to, and is carried by said fabric jacket.

4. The neckpiece defined in and according to claim 3, and wherein said ornate means is characterized by longitudinally positioned first and second ribbons made of necktie material, said ribbons extending lengthwise of the forward surface of the fabric-jacketed-form and being attached to the jacketing material, adjacent longitudinal oriented edges of said ribbons overlapping each other and presenting an appearance resembling a cummerbund.

5. The neckpiece defined in and according to claim 4, and wherein said ornate means also includes a depending puff which is segmental in front elevation and is pleated to present a desirably gathered appearance.

6. The neckpiece defined in and according to claim 5 and, in combination, a plurality of individual optionally usable relatively small pennant-like pendants having upper ends joined by snap-fasteners to a rearward lower marginal edge portion of said jacket and free lower ends visibly suspended below a bottom marginal edge of said puff.

7. A ready-made neckpiece comprising a fabric-covered bendably pliant form of predetermined size and shape having a front face substantially covered by longitudinally extending complementary overlapping ribbons presenting a miniaturized cummerbund effect, a symmetrically arranged depending attractively pleated and gathered grooming puff carried by and depending below said fabric-covered form, and clip means attached to an upper median edge portion of said form and provided with an attaching and retaining hook.

8. The neckpiece defined in and according to claim 7, and in combination, a plurality of individual selectively usable relatively small pennant-like pendants having upper ends joined by snap-fasteners to a rearward lower marginal edge portion of said form and free lower ends visibly suspended below a bottom marginal edge of said puff.

9. The neckpiece defined in and according to claim 7, and wherein said puff is segmental in front elevation, and also wherein said hook extends to a locale above said median edge portion.
